[57] CLAIM

The ornamental design for a pump for liquids, as shown and described.

DESCRIPTION

FIG. 1 is a top perspective view of a pump for liquids showing our new design;

FIG. 2 is a top plan view;

FIG. 3 is an elevational view of both left and right sides;

FIG. 4 is an elevational view of both left and right ends;

FIG. 5 is bottom perspective view; and,

FIG. 6 is a bottom plan view.

The broken line showing of a drive mechanism in FIG. 4 is for illustrative purposes only and forms no parts of the claimed design.

FIG. 2

FIG. 3

FIG. 4
